UNITED STATES PATENT OFFICE.

JOSEPH KEEFE, OF BOSTON, MASSACHUSETTS, ASSIGNOR TO CHARLES S. KNOWLES, OF NEW BEDFORD, MASSACHUSETTS.

ELECTRIC SWITCH.

967,932.

Specification of Letters Patent. Patented Aug. 23, 1910.

Application filed May 6, 1909. Serial No. 494,445.

To all whom it may concern:

Be it known that I, JOSEPH KEEFE, of Boston, in the county of Suffolk and State of Massachusetts, have invented a new and 5 useful Electric Switch, of which the following is a specification.

The objects of my invention are to improve the construction and operation of electric switches, and one feature of my invention 10 consists in means for limiting the movement of the switch controlling means.

Another feature of my invention is the means for positioning the push buttons.

Another feature is a removable operating 15 spring.

In the drawings Figure 1 is an elevation of a switch embodying my invention; Fig. 2 is a bottom plan; Fig. 3 is a central, vertical section; and Fig. 4 is a detail herein- 20 after described.

Within casing A, which is of insulating material, are the binding posts a , a and contact terminals a' , a'' , suitably held in place. Supporting plate B and cover A' 25 may be held to the casing by screws or other attaching means, and are apertured as usual. Suspended from plate B is bearing yoke D which carries pin d forming the pivot of the rock arm. This rock arm comprises two 30 parallel members E and E' which are connected at their ends and pivoted in slots g , g formed in members G, G' which members have wings g' , g'' to coöperate with the under side of plate B for purposes to be herein- 35 after explained. Upon members G, G' are rigidly mounted the push buttons H and H'.

Near the bottom of each of the members E and E' is a hole e from which leads a short passage e' . Pivoted in the holes e , e 40 is abutment K which is preforated and which has projections k , k , the projections normally oscillating in the holes e , e but capable of being slid out through the small 45 passages e' if it is desired to remove the spring in the manner hereinafter described.

Pivoted at L to yoke D is a tilting lever comprising parallel plates l and l' connected by pin l^2 and having shoulders l^1 , l^2 to engage pin d to limit the movement of the 50 lever. Pin M has an enlarged head m , the latter being notched to engage pin l^2 . Upon the body of this pin is coiled spring N, the head of the pin serving as an abutment for one end of the spring and abutment K being 55 opposed to the other end of the spring, the

small end of the pin passing through the perforation in abutment K. It will be clear that the spring can be readily removed and replaced either by forcing abutment K downward and drawing its projections out through 60 passages e' , and then slipping the abutment off the pin M, or by forcing the head of the pin M off the pin l^2 and then withdrawing the bolt from abutment K. This construction not only makes the switch very easily 65 assembled but also provides for quick repairing or replacing of worn parts. Mounted to oscillate with the tilting lever is hub P carrying terminals f , f' which make and break with terminals a' and a'' .

In using my switch, assuming the parts to be in the positions shown, the button H is pushed down and as it descends the pivot at the end of the rock arm moves outwardly in slot g until said end is opposite the pivot 70 of the rock arm and from that time on said end part moves inwardly in said slot, the result being that the push button occupies a position at right angles to plate B during its reciprocation. Pressing down the button stores power in the spring and oscillates it by carrying the upper abutment of the spring toward a line extending from the pivot L of the lever to the pin l^2 of the lever. When the upper abutment passes that line 75 of the rock arm and from that time on said end part moves inwardly in said slot, the result being that the push button occupies a position at right angles to plate B during its reciprocation. Pressing down the button stores power in the spring and oscillates it by carrying the upper abutment of the spring toward a line extending from the pivot L of the lever to the pin l^2 of the lever. When the upper abutment passes that line 80 of the rock arm and from that time on said end part moves inwardly in said slot, the result being that the push button occupies a position at right angles to plate B during its reciprocation. Pressing down the button stores power in the spring and oscillates it by carrying the upper abutment of the spring toward a line extending from the pivot L of the lever to the pin l^2 of the lever. When the upper abutment passes that line 85 of the rock arm and from that time on said end part moves inwardly in said slot, the result being that the push button occupies a position at right angles to plate B during its reciprocation. Pressing down the button stores power in the spring and oscillates it by carrying the upper abutment of the spring toward a line extending from the pivot L of the lever to the pin l^2 of the lever. When the upper abutment passes that line 90 of the rock arm and from that time on said end part moves inwardly in said slot, the result being that the push button occupies a position at right angles to plate B during its reciprocation. Pressing down the button stores power in the spring and oscillates it by carrying the upper abutment of the spring toward a line extending from the pivot L of the lever to the pin l^2 of the lever. When the upper abutment passes that line 95 of the rock arm and from that time on said end part moves inwardly in said slot, the result being that the push button occupies a position at right angles to plate B during its reciprocation. Pressing down the button stores power in the spring and oscillates it by carrying the upper abutment of the spring toward a line extending from the pivot L of the lever to the pin l^2 of the lever. When the upper abutment passes that line 100 of the rock arm and from that time on said end part moves inwardly in said slot, the result being that the push button occupies a position at right angles to plate B during its reciprocation. Pressing down the button stores power in the spring and oscillates it by carrying the upper abutment of the spring toward a line extending from the pivot L of the lever to the pin l^2 of the lever. When the upper abutment passes that line 105 of the rock arm and from that time on said end part moves inwardly in said slot, the result being that the push button occupies a position at right angles to plate B during its reciprocation.

The advantages of my switch will be clear from the above description, especially the efficiency of operation and the improvements in construction.

What I claim is:

1. An electric switch comprising a pivoted lever; a spring to operate said lever; a rock-arm for actuating the spring; an apertured supporting member; and push buttons 110

2
mounted to reciprocate through said member and each having a sliding connection with the rock-arm and each having means to engage said member to position said push buttons at right angles with said member when the push buttons are in their outermost position.

5 2. An electric switch comprising a pivoted lever; a spring to operate said lever; a rock-arm for actuating the spring; an apertured supporting member; and push buttons

10 mounted to reciprocate through said member and each having a sliding connection with the rock arm and each having oppositely-disposed projections to engage said member to position said push buttons at right angles with said member when the push buttons are in their outermost position.

15 JOSEPH KEEFE.
